DESIGN FOR A GAME BOARD

Jerome U. Bihl, San Marino, Calif.

Application August 20, 1945, Serial No. 121,508

Term of patent 3½ years

(Cl. D34—5)

To all whom it may concern:

Be it known that I, Jerome U. Bihl, a citizen of the United States, residing at San Marino, in the county of Los Angeles and State of California, have invented a new, original, and ornamental Design for a Game Board, of which the following is a specification, reference being had to the accompanying drawing, forming part thereof; the game board is of conventional thickness.

The figure is a plan view of a game board, showing my new design.

I claim:

The ornamental design for a game board, as shown and described.

JEROME U. BIHL.
